CONTROL APPARATUS FOR COMBINED FLUID COMPRESSORS AND FREE PIS- TON MACHINES

Arthur J. Bent, Pittsburgh, Pa., assignor to West-
inghouse Air Brake Company, a corporation of
Pennsylvania

Application May 25, 1948, Serial No. 28,996

9 Claims. (Cl. 230—56)

1

This invention relates to free piston machines and more particularly to the type for compressing air and the principal object of the invention is the provision of improved means for controlling starting and running thereof.

More particularly the invention relates to control apparatus arranged for operation by an operator to effect starting of a free piston air compressor and means automatically operative after starting to control running of the compressor in accordance with the pressure of delivered fluid.

Other objects and advantages of the invention will become apparent from the following more detailed description thereof.

In the accompanying drawings: Fig. 1 is a diagrammatic view of a free piston machine and of a control apparatus therefore embodying the invention; Fig. 2 is a sectional diagrammatic view of a portion of the control apparatus shown in elevation in Fig. 1; Figs. 3 and 4 are sectional views of positioning and locking cylinders, respectively, shown in elevation in Fig. 1; Fig. 5 is a sectional view of a direct bounce governor device shown in elevation in Fig. 1; Fig. 6 is an enlarged view of a portion of said direct bounce governor device; and Fig. 7 is a diagrammatic view of a timing valve device shown in elevation in Fig. 1.

Description

In the drawing, reference numeral 1 indicates generally a free piston machine of well-known structure comprising a casing containing two opposed and identical, diesel type operated, air compressing units 2 and 3 each of which comprises a power piston 4 and integrally connected air compressing and direct bounce pistons 5 and 6, respectfully. The two power pistons 4 cooperate with the casing of the machine to form a power chamber 7 into which fluid is adapted to be injected by way of a nozzle 8 for compression ignition upon said pistons obtaining a chosen inner position. The power thus developed is adapted to drive the piston assemblies of the two units outwardly on an air compressing stroke. As the power pistons thus move outwardly they are adapted to first uncover an exhaust port 9 for escape of burnt gases from chamber 7 and then a scavenger port 10 to allow entry of fresh air to said chamber for scavenger purposes.

At the power piston side of each air compressing piston 5 is a scavenger compressing chamber 11 having a connection with atmosphere by way of an inlet valve 12 and a discharge connection with a scavenger receiver 13 by way of a dis-

2

charge valve 14, the scavenger receiver being connected to said chamber in both compressing units and to the scavenger port 10 in the casing, whereby during running, reciprocation of pistons 5 will constantly provide a supply of compressed air for scavenging the power chamber 7.

At the opposite side of each air compressing piston 5 is an air compressing chamber 15 having an intake opening with atmosphere past an inlet valve 16 and a delivery opening past a discharge valve 17 to a compressed air receiving pipe 18. The pipe 18 is connected to the air compressing chamber 15 in both compressor units, to a storage reservoir 18a and to a control valve device 19. It will be apparent that upon running of the two compressor units 2 and 3, reciprocation of the air compressing pistons 15 will alternately draw air from atmosphere past inlet valves 16 into chambers 15 and then compress such air past the discharge valves 17 into pipe 18 and storage reservoir 18a. The storage reservoir 18a constitutes a source of compressed air for any desired purpose.

At the outer end of each direct bounce piston 6 is a direct bounce chamber 20 in which air is adapted to be compressed on the outward power and air compressing stroke of the two piston assemblies to provide energy for stopping said pistons and for returning them on a compression stroke to provide compression ignition. The two direct bounce chambers 20 are in permanent communication with each other by way of a pipe 21 which also connects with the control valve device 19.

The piston assemblies of the two air compressing units are connected together for symmetrical movement by two pairs of oppositely operating toothed racks 22 and 23 cooperating with an interposed pinion gear 24 secured to operate a rock shaft 25 which may be journaled in the casing of said units. The pairs of racks may be arranged at opposite sides of the power pistons 4 with the two racks 22 connected at one end to a bar 26 extending through an opening in one of said pistons and suitable slots 27 in the casing, while the two racks 23 are connected at one end to a similar bar 28 extending through an opening in the other piston 4 and similar slots 29 in the casing, said slots being of such length as to permit full stroking of the piston assemblies without fouling on the casing. The bar 26 is rigidly connected to the respective piston 4 and secured thereto at its center by a pin 26a while the opening in the other piston through which the rod 26 extends is wider in the direction of the axis of

the piston than the width of rod 28 to permit rod 28 to rock slightly on a pin 28a secured at its longitudinal center to the respective piston 4 for equalizing pressure transmitted by both rods 26 and 28 to the respective racks 22, 23.

The casing is provided beyond each direct bounce chamber 20 with a safety space 30 which during normal running of the compressor constitutes a part of said chamber. The safety spaces 30 are adapted to receive the direct bounce pistons 6 in case of overstroke of the piston assemblies during running to provide an air cushion to stop the assemblies before contact of said pistons with the end walls of said spaces. Also in starting the compressor 1 the direct bounce pistons 6 are adapted to move into the safety spaces, 30, as will be later described.

For moving the piston assemblies apart to their extreme outer positions for starting the compressor and in which the direct bounce pistons 6 will be disposed in the safety spaces 30 two like positioning cylinder devices 31 and 32 are provided. For illustration purposes, these cylinder devices are shown at the same side of the compressor and oppositely arranged for acting on the opposite free ends of the respective racks 22, 23.

Each of the positioning cylinder devices 31, 32 comprises (Fig. 3) a casing containing a piston 33 provided with an axially arranged cylindrical piston rod 34 extending through and having sliding contact with a bearing element 35. A pre-compressed spring 36 encircling rod 34 is supported at one end on element 35 while its opposite end bears against one side of piston 33 for urging said piston to a normal or rest position, in which it is shown in the drawing, when a pressure chamber 37 is void of fluid under pressure. The bearing element 35 is held in the casing against the force of spring 36 by engagement with a ring 38 secured in the casing. Substantially midway of the length of piston rod 34 said rod has a stop shoulder 39 arranged for contact with the bearing element 35 to limit movement of piston 33 against spring 36.

Slidably mounted in the piston rod 34 is a piston 40 one side of which is open to chamber 31. Extending from the opposite side of piston 40 and through a suitable bearing provided in a closed end wall 42 of rod 34 is a rod 41. Slidably mounted on the rod 41 within the sleeve 34 is a spring 43 supporting device 43 subject on opposite ends to pressure of two oppositely extending compressed coil springs 44, 45, respectively, which encircle the rod 41. The spring 44 is supported at the end opposite that engaging the supporting device 43 by the end wall 42 of piston rod 34, while the opposite end of spring 45 bears against the piston 40, the purpose of said springs being to urge said piston to the position in which it is shown in the drawing with respect to piston 33 when chamber 37 is void of fluid under pressure. To prevent piston 40 moving out of its cylinder a ring 45a is secured to rod 41 outside of the casing for contact with the closed end wall 42 of the cylindrical rod 34.

The rods 41 of the two positioning cylinders 31 and 32 are arranged for engagement with the ends of the respective racks 22 and 23. When, as during running of the compressor, the rods are in their fully retracted position, in which they are shown in the drawing, racks 22, 23 are adapted to reciprocate with the power pistons 4 without contacting said rods. For starting the machine, preparatory to running, fluid under pressure is adapted to be supplied to pressure chambers 31

in the two positioning cylinders 31, 32 through a common pipe 46 by operation of the control device 19. In each positioning cylinder device the pressure acting on the piston 33 is adapted to move said piston against spring 36 until shoulder 39 engages the bearing element 35 for projecting the cylindrical rod 34 from the casing. At substantially the same time, the piston 40 will be moved in the rod 34 by pressure of fluid in chamber 37 and actuate its rod 41 first into contact with the respective rack 22 or 23 and then through said rack move the respective piston assembly 4, 5 and 6 to the position preliminary to starting in which said piston 6 will be disposed in the respective safety space 30.

A fluid pressure operable, spring released, locking device 47 is associated with each of the opposite ends of the two rods 26, 28 for cooperation therewith to hold the two piston assemblies in their outermost positions preliminary to starting, against pressure of fluid in the direct bounce chambers 20 which will become effective by leakage into the safety spaces 30 over the ends of the direct bounce pistons 6, as will be later described.

Each locking device (Fig. 4) comprises a casing 48 adapted to be fixed with respect to the compressor casing. Slidably mounted in casing 48 is a piston 49 provided at one side with a rod 50 extending through a non-pressure chamber 51 and a suitable bore in the end wall thereof to the exterior of the casing. A precompressed spring 52 contained in chamber 51 and encircling rod 50 is supported at one end on the casing and bears at the opposite end against one side of piston 49 for urging said piston to its normal rest position, in which it is shown in the drawing, upon release of fluid under pressure from a pressure chamber 53 at the opposite side of said piston. Movement of piston 49 in the opposite direction against spring 52 is adapted to be limited by contact between said piston and a boss 49a encircling the rod 50. The pressure chambers 53 in the several locking devices are all connected to a common control pipe 54 leading to the control device 19. In practice the distance by way of pipe 54 from the control device 19 to all of the locking devices 47 is substantially the same in order to provide for operation of said devices in unison.

Each locking device 47 further comprises an arm 55 projecting from casing 48 and fulcrumed on a pin 56 carried by said arm is the knee of a bell crank 57 the end of one arm of which is connected by a pin 58 to the projecting end of piston rod 50. A roller 59 is mounted on a pin 60 carried in the end of the other arm of bell crank 57. The locking devices 47 adjacent the opposite ends of bar 26 are disposed with the ends carrying the rollers 59 arranged opposite to the ends carrying the rollers in the other two locking devices, and each of the opposite ends of the two bars 26, 28 is provided with a locking surface 61 for contact by the respective roller 59 with the piston 49 in contact with the stop boss 49a in their respective locking device, said piston being movable to this position against spring 52 upon supply of fluid under pressure to chamber 53 by way of pipe 54, as will be hereinafter described. The angularity of surfaces 61 with respect to the angular position of the respective bell-cranks 57 when pistons 49 are in contact with boss 49a is such as to permit pressure of fluid in the direct bounce chambers 20 and safety spaces 30 acting on the piston assemblies and through the rods 26, 28 on the rollers 59 in the locking devices 47 to displace said rollers out of the path of movement of said

rods, when fluid under pressure is released from pressure chambers 53.

Reference numeral 62 indicates a fuel injector of any well-known type arranged to be operated by a cam 63 on the rock shaft 25 at the proper point in the inward stroke of the piston assemblies to supply fuel to the power chamber 7 by way of nozzle 8 to provide compression ignition for driving the piston assemblies apart on their power, air compressing stroke. Adjustment of the injector 62 to vary the fuel supply is obtained by a conventional rack 64 having a run position such as that in which it is shown in the drawing to provide a maximum amount of fuel for starting and normal running of the machine and being movable into the injector for reducing the fuel supply.

According to the invention I provide apparatus for controlling operation of the structure so far described, and thereby for controlling compressing of air by the free piston units 2, 3 into the storage reservoir 18a and for automatically limiting the pressure in said reservoir during running of the machine.

The invention comprises in part the control valve device 19, above mentioned, which in turn comprises a bracket 65 upon which is mounted a manually operable operator's starting valve device 66, a feed valve device 67a of any well-known structure, a vent valve device 67, a shuttle valve device 68, a sequence valve device 69 and an unloading valve device 70.

The operator's starting valve device 66 (Fig. 2) comprises a casing having a chamber 71 containing a supply valve 72 arranged to cooperate with a seat 73 for controlling communication between said chamber and a chamber 74 by way of an axial passage 75 encircled by said seat and one or more passages 76 connecting passage 75 to chamber 74. A release valve 77 contained in chamber 74 is arranged to cooperate with a seat on the end of an axially movable cylindrical plunger 78 for controlling a fluid pressure release communication between said chamber and the interior of said plunger which is open to atmosphere through a radial port 79 in the plunger, a chamber 80 encircling said plunger and a passage 81. A pin 82 of small diameter and extending through the axial bore 75 connects the adjacent side of the supply and release valves 72 and 77. A spring 83 in chamber 71 acts on the supply valve 72 for seating it. A casing shoulder 84 is provided for contact by the release valve 77 to permit plunger 78 to move away from it for opening communication past said valve from chamber 74 to the interior of said plunger and thereby to atmosphere.

The end of plunger 78 opposite the seat for release valve 77 extends through a bore in a cap nut 85 for engagement by an operator's lever 86. Within the chamber 80, a collar 87 on plunger 78 is provided to contact cap nut 85 to limit unseating movement of said plunger from the release valve, and a spring 88 contained in said chamber and acting on said collar is provided to effect such movement of said plunger.

The operator's lever 86 has at one end a slot 89 and extending through said slot and carried by the casing is a fulcrum pin 90. The lower end of lever 86 is beveled and interposed therebetween and the casing is a spring 91 which is under pressure and which has a line of action passing through said lever below the axis of pin 90, whereby the spring not only acts to elevate the lever on said pin but also urges it in a

counter-clockwise direction about said pin. The lever 86 has a protecting boss 92 for engaging the casing in the elevated position of said lever to hold the lever out of contact with the projecting end of plunger 78. Depressing of lever 86 downwardly against spring 91 to a position defined by pin 90 engaging the opposite end of slot 89 will align the boss 92 for engagement with plunger 78.

The supply valve chamber 71 is open to a fluid pressure supply passage 93 adapted to be constantly supplied with fluid at a chosen pressure, such as 500 pounds, by operation of the feed valve device 67a to supply fluid thereto from a source of higher pressure such as 650 pounds normally contained in a high pressure reservoir 94 and connected to the feed valve device by a pipe 95. The release valve chamber 74 is open by way of a passage 106 to pipe 46 connected to the positioning cylinder devices 31, 32.

The vent valve device 67 comprises a valve 96 contained in a chamber 97 for controlling communication between said chamber and a chamber 98a which is open to atmosphere through a passage 99. Chamber 97 is open by way of a passage 108 in the bracket 65 to pipe 18 leading to the air compressing chambers 15 and storage reservoir 18a, as well as to the unloading valve device 70. The vent valve device 67 further comprises a piston 101 connected by stem 102 to valve 96 and open at one side to a pressure chamber 103 which is connected to the bracket passage 108. Upon supply of fluid under pressure to chamber 103 the piston 101 is adapted to unseat valve 96 for opening chamber 97 to the atmospheric passage 99. A spring 104 acting on piston 101 is adapted to operate same upon release of fluid under pressure from chamber 103 to permit seating of valve 96 by a spring 96a. The piston chamber 103 is open to passage 106.

The shuttle valve device 68 comprises a poppet valve 126 contained in a chamber 127 which is open by way of a passage 128 to pipe 21 leading to the direct bounce chambers 20. The valve 126 is arranged to cooperate with a seat 129 at one side for controlling communication between chamber 127 and a pipe 128a leading to a direct bounce pressure governor device 130. The valve 126 is cooperative with a seat 131 at its opposite side to control communication between chamber 127 and an atmospheric passage 132.

The valve 126 is connected to one end of a stem 133 extending through the encircling seat 131 and then through a bore in the casing into a chamber 134 at one side of a piston 135 to which the opposite end of said stem is connected. A spring 136 in chamber 134 acts on piston 135 for actuating same to unseat the valve 126 from seat 129 and to seat it on seat 131 when a chamber 137 at the opposite side of said piston is void of fluid under pressure. Upon supply of fluid under pressure to chamber 137 the piston is adapted to shift valve 126 into engagement with seat 129.

The sequence valve device 69 comprises a poppet valve 107 contained in a chamber 108 which is open to pipe 54 leading to the locking devices 47. The valve 107 has two positions in one of which it is arranged to cooperate with a seat 109 for disconnecting chamber 108 from an atmospheric passage 110 and for opening said chamber through a seat 111 to a passage 112 connected by a pipe 113 to a timing valve device 114. In the other position of valve 107 in which

it will be in engagement with seat 111 the chamber 108 is adapted to be disconnected from passage 112 and opened to passage 110.

The valve 107 is connected to one end of a stem 115 extending through the seat 111, passage 112 and a bore in the casing. Connected to the opposite end of stem 115 is a piston 116 for moving the valve 107 to its different positions, said piston being slidably mounted in a bore through an element 117 secured in the casing of the device and separating a chamber 120 at the side of said piston from which the stem 115 projects from an atmospheric chamber 121 at the opposite side. The chamber 120 is provided around an annular seat rib 123 and within said rib is a chamber 124 encircling the stem 115 and open to passage 128. The diameter of the seat rib 123 is less than that of piston 116 so that when said piston is in contact therewith less than the full face of the piston will be exposed to chamber 124 within said rib. When the piston 116 is disengaged from seat rib 123 chambers 120 and 124 are in effect one chamber. A spring 125 contained in chamber 121 acts on the piston 116 for urging it into contact with seat rib 123 with a chosen force.

The unloading valve device 70 comprises a check valve 141 contained in a chamber 142 and arranged to control communication by way of a bore 143 between said chamber and a passage 144. The passage 144 is connected on the one hand through an air strainer 145 to passage 100 and thence by way of pipe 18 to the storage reservoir 18a, and on the other hand, to an air intake pipe 146 for a high pressure auxiliary air compressor 147. A discharge pipe 148 from the compressor 147 is connected to chamber 142 in the unloading device 70.

In the unloading device 70 a bias spring 149 acts on the check valve 141 for urging it to its seat. Extending through the passage 144 and bore 143 and engaging the check valve 141 is a pin 150 which is connected to a piston 151 slidably mounted in the casing. At the check valve side of piston 150 is a non-pressure chamber 152 open to atmosphere through a vent 153 and containing a spring 154 acting on said piston for urging it with a chosen force in a direction away from check valve 141 to permit seating of said valve by spring 149, such movement of said piston being limited by contact with the casing. A ring seal 153a carried in the casing has sealing and sliding contact with the peripheral surface of pin 150 to prevent leakage of fluid under pressure from passage 144 to the atmospheric chamber 152. At the opposite side of piston 151 is a pressure chamber 154a which is open to a passage 155 in turn open to pipe 95 leading to the high pressure reservoir 94.

Associated with the unloading device is a check valve 156 contained in a chamber 157 for closing communication between said chamber and a passage 158 connecting the unloading check valve chamber 142 to the discharge pipe 148 from compressor 147. A bias spring 159 in chamber 157 acts on the check valve 156 for urging it to its seat. The chamber 157 is open to passage 155.

The high pressure air compressor 147 may be of any suitable type capable of operation by oscillation of shaft 25, which is driven by the free piston machine 1 through the medium of one of the pairs of racks 22, 23 and the interengaging pinion 24, to take air under pressure from pipe 146, and hence from the storage reservoir 18a, and to compress it to a higher pressure into pipe 148 and thence into the high pressure 75

reservoir 94. The pressure of air in the storage reservoir 18a, as charged by the free piston machine as will be hereinafter described, may be of any degree up to for example 100 pounds but normally between for instance 90 and 100 pounds, while that delivered by the compressor 147 for supply to the high pressure reservoir 94 may for example be around 650 pounds.

The direct bounce governor device 130 (Fig. 5) may comprise a casing having a chamber 160 arranged to be constantly supplied with fluid from the high pressure reservoir 94 at the reduced pressure provided by the feed valve device 67a by way of passage 93 in the control valve device 19, a pipe 161 and a passage 162 in said governor device. The chamber 160 contains a supply valve 163 arranged to cooperate with a seat 164 for controlling flow of fluid under pressure from said chamber to a chamber 165 which is open by pipe 128a to the shuttle valve device 68. Encircling the seat 164 is an element 166 having a bore in which the valve 163 is adapted to move, said bore being tapered outwardly from said seat for cooperation with said valve to provide a controlled and variable degree of opening past said valve according to the degree it is unseated from seat 164. A stem 167 has one end connected to valve 163 and a spring 168 contained in chamber 160 acts on said stem for urging said valve toward seat 164. The stem 167 is connected with and projects from one side of a piston 169 through the chamber 160 and is constantly subject on said one side to pressure of fluid in said chamber. The opposite side of piston 169 is subject to pressure of fluid in a chamber 170 which is constantly open through a choke 171 in said piston and a passage 172 in stem 167 to chamber 160.

A poppet valve 173 contained in a chamber 174 open to chamber 170 is arranged to cooperate with a seat in the casing to control communication between said chamber 174 and a passage 175 which is open to chamber 165. A release valve 176 (Fig. 6) coaxially arranged with respect to but spaced from the valve 173 is adapted to cooperate with a seat on a movable element 177 for controlling a fluid pressure release communication between passage 175 and a passage 178 in said element. A plunger 179 slidably mounted in a suitable bore in the casing has opposite ends in engagement, respectively, with the valves 173 and 176. A spring 180 contained in chamber 174 acts on the valve 173 for urging it toward its casing seat. A shoulder 181 in the casing is arranged for contact by valve 176 to permit unseating of the element 177 therefrom.

The element 177 is slidably mounted in a bore in the casing and has a sealing ring 182 in sealing and sliding contact with the wall of said bore to prevent leakage of fluid under pressure between passage 175 open to one side of said ring and a chamber 183 at the opposite side. The element 177 constitutes an extension of a diaphragm follower 184 contained in chamber 183 and clamped centrally to one side of a flexible diaphragm 185 by the cooperation thereof and a securing nut 186 engaging the opposite side of said diaphragm. The diaphragm is clamped around its edge in the casing with chamber 183 at one side and a chamber 187 at the opposite side. Chamber 183 may be open by way of a pipe 188 to one of the two direct bounce chambers 20. The pipe 188 has a relatively small flow capacity so that upon reciprocation of the two direct bounce pistons 6, as will be hereinafter described, a substantial

mean of the pressure developed in said direct bounce chambers at opposite ends of the stroke of said pistons will be constantly effective in chamber 183 on the one side of the diaphragm. Chamber 187 at the opposite side of the diaphragm may be constantly supplied with fluid under pressure from passage 162 by way of a choke 189.

The diaphragm follower 184 comprises a stud portion 190 extending centrally through the diaphragm for cooperation with the nut 186 and said stud portion has an axial counterbore to which passage 178 from the release valve 176 opens and in which is slidably mounted one end of a fluid conductor 191. The fluid conductor extends through chamber 187 and its opposite end is slidably mounted in a casing bore which is open to atmosphere through a passage 192, whereby passage 178 is constantly vented. The opposite ends of the conductor 191 are spherical and each carries a sealing ring 193 having sealing and sliding contact with the wall of the respective bore for preventing leakage of fluid under pressure from one side to the opposite side of the ring. The cross-sectional area of the end of the conductor 191 disposed in the bore of the follower stud 190 is greater than the cross-sectional area of the movable element 177, so that the area of the diaphragm subject to pressure of fluid in chamber 187 is somewhat less than that subject to pressure of fluid in chamber 183, whereby in case of equal pressures of fluid in chambers 183, 187, a slight bias force will be provided acting in the direction of chamber 187.

The direct bounce governor device 130 further comprises a member 194 adjustably mounted in a bore in the casing and having a counterbore 195 closed at one end by a plug 196, while extending from the opposite end through a plug 197 secured in one end of said bore and into an atmospheric chamber 198 is an adjusting stem 199. The plug 196 has an axial bore encircled within counterbore 195 by a valve seat provided for engagement by a poppet valve 200 contained in said counterbore. A bias spring 201 in counterbore 195 acts on the valve 200 for urging it to its seat. Counterbore 195 is constantly open to diaphragm chamber 187 by way of one or more ports 202 therethrough, an annular cavity 203 provided in the exterior surface of plunger 194 and a passage 204.

A bias spring 205 contained in chamber 198 is interposed between the casing and a washer 206 secured to stem 199 for holding said stem, the plunger 194 and the associated seat for valve 200 in a chosen position in the casing determined by adjustment of an adjusting screw 207 screw-threaded in the casing and extending into chamber 198 wherein it engages the end of stem 199.

At the outer or right-hand end of plug 196 is a chamber 208 open by a passage 209 to a chamber 210 at the opposite end of plunger 194, said passage being also open to passage 175, and thence to chamber 166 and thereby the direct bounce chambers 20. Suitable sealing rings 211 carried by the plunger 194 are provided to prevent leakage of fluid under pressure from cavity 203 to either chamber 208 or 210.

A plunger 212, slidably mounted in suitable bores in the casing in coaxial alignment with the valve 200 in the governor device 130, is so disposed that the end of said plunger projecting from said device is aligned for engagement by the end of one of the racks for instance a rack 22 as shown in the drawing, near the end of the

compression stroke of the power pistons 4. The plunger 212 comprises a relatively large portion 213 terminating in a chamber 214 wherein one end is connected to a smaller part 215 which projects outside of the casing for engagement with the rack 22. Projecting from the opposite end of the large portion 213 into chamber 208 is a smaller portion 216 and projecting from the smaller portion 216 is a portion 217 extending through chamber 208 and, with clearance, through an axial bore in plug 196 for engaging the poppet valve 200. Chamber 214 is open through a passage 217a to the annular cavity 203 so as to be constantly charged with fluid under pressure from diaphragm chamber 187. The area of plunger 212 thus subject to pressure of fluid in chamber 214 is slightly greater than the area subject to pressure of fluid in chamber 208 whereby a force is created which will constantly bias said plunger in the direction of and against the valve 200 but insufficient to unseat said valve against spring 201.

The timing valve device 114, except as herein-after noted, may be identical to the starting valve device 66 and the fluid pressure supply pipe 161 is connected to the supply valve chamber 71 thereof while the pipe 113 is connected to the release valve chamber 74.

The plunger 78 of the timing valve device 114 is however, provided with an enlarged piston-like portion 231 (Fig. 7) subject on one end to pressure of fluid in the release valve chamber 74 and on the opposite end to atmospheric pressure in chamber 80. The area of portion 231 is such that when subject to pressure of fluid in chamber 74, said portion will move the plunger 78 against spring 88. The shoulder 84 for contact with the release valve 77 to unseat it from the end of plunger 78 is so disposed as to permit a greater movement of said plunger after seating of the supply valve 72 before unseating of the release valve 77 occurs than is the case with the starting valve device 66, for reasons which will be herein-after described. A light bias spring 232 acts on the release valve 77 to urge it out of contact with shoulder and into contact with pin 92 upon release of fluid under pressure from chamber 74.

The timing valve device 114 is so arranged with respect to the free piston machine that the plunger 78 thereof will be operated, as by engagement of the rack connecting bar 28, to close the release valve 77 and open the supply valve 72 when, and only when, the direct bounce pistons are at the end of their outward stroke disposed in the safety spaces 30, and to permit closing of said supply valve upon slight movement in the opposite direction followed by opening of the release valve after the direct bounce pistons 6 are urged out of the safety spaces 30 a chosen distance.

A motor 218 is provided for adjusting the rack 64 of the fuel injector 62. This motor comprises a casing containing a flexible diaphragm 219 at one side of which is a chamber 220 open to pipe 18 whereby said diaphragm is adapted to be constantly subjected in said chamber to the pressure of fluid in the storage reservoir 18a.

At the opposite side of diaphragm 219 is a non-pressure chamber 223 containing a plunger 224 engaging at one end the adjacent side of diaphragm 219 and extending outwardly from the casing with its opposite end operatively connected to a lever 222 between its ends. One end of lever 222 is fulcrumed to a lug 225 projecting from the casing of the motor while its oppposite

11

end is operatively connected by a link 226 to rack 64 of the fuel injector 62. A shoulder 227 on stem 224 is provided for engagement with a stop nut 228 adjustably secured in the casing for limiting movement of said stem and of diaphragm 219 by pressure of fluid in chamber 220 to a degree for positioning lever 222 and thereby the fuel rack 64 to what may be called an idle position. A spring 229 in chamber 223 acts on diaphragm 219 in opposition to pressure of fluid in chamber 220.

The pressure of spring 229 is such as to prevent movement of the diaphragm from the position in which it is shown in the drawing while the pressure of fluid in the storage reservoir 18a acting in chamber 220 is less than the chosen pressure, such as 90 pounds. When the pressure of fluid in reservoir 18a and chamber 220 is increased to above this chosen pressure the diaphragm 219 is adapted to be deflected thereby in accordance with such increase until at the time a chosen higher pressure, such as 100 pounds, is obtained the shoulder 227 on plunger 224 will contact stop nut 228. With the diaphragm 220 in the position in which it is shown in the drawing the lever 222 and rack 64 will be positioned to supply the maximum amount of fuel to the nozzle 8. It will therefore be seen that for starting the free piston machine and during running thereof until the pressure of fluid in the storage reservoir 18a is increased to the chosen pressure of 90 pounds the supply of fuel to the machine will be constant and of a maximum degree, following which the fuel supply will be reduced in proportion to further increase in pressure in reservoir 18a until at the time the higher pressure of 100 pounds is reached the fuel supply will be so reduced that the machine will merely idle. When idling there will be no discharge of air from the air compressor chambers 15, as will be brought out later in detail.

A cut-out valve 230 is provided in the connection of pipe 95 to the feed valve device 67a for closing communication between said pipe and feed valve device when the free piston compressor units are stopped and for opening said communication for starting and during running of said units.

Operation

In operation, let it be assumed that the free piston air compressor is stopped and that the high pressure reservoir 94 is charged with fluid at substantially normal pressure, such as 650 pounds, from previous operation of the auxiliary high pressure compressor 147 in a manner which will become later apparent. When the high pressure reservoir charged with fluid under pressure it will be noted that the check valve 153 associated with the unloading valve device 70 functions to hold the fluid in said reservoir against reverse flow through passage 155. When the free piston compressor is stopped the cut-out valve 230 will also be closed to disconnect the high pressure reservoir 94 from the feed valve device 67a.

In order to prepare for starting the free piston compressor, the cut-out valve 230 will be opened to permit fluid under pressure from the high pressure reservoir to flow to the feed valve device 67a which will operate to supply fluid therefrom at the desired reduced pressure, for example 500 pounds, to passage 93 and thence to chamber 71 in the starting valve device 66 and also from said passage to pipe 181 leading to the corresponding chamber 71 in the timing valve

12

device 114, and let it be further assumed that the supply valve 72 in both of said devices is seated at this time.

Fluid supplied by the feed valve device 67a to pipe 161 will also flow into chamber 190 and gradually through choke 189 into chamber 187 of the direct bounce governor device 139.

When the free piston compressor is stopped, in a manner which will be later described in detail, the piston assemblies will be substantially in their innermost position and valve 230 in the direct bounce governor device 139 will therefore be open sufficiently to dissipate to atmosphere past the valve 176, which will be open, the fluid under pressure thus supplied to chamber 187, at a rate exceeding the rate of supply through choke 189, so that there will be no change in position of the parts of the direct bounce governor device upon initially opening the cut-cut valve 230.

To now start the free piston air compressor the operator will grasp lever 86 and turn it about pivot pin 90 in a clockwise direction against the force of spring 91 until the lug 92 on said lever 25 clears the projecting end of plunger 78. The lever 86 will then be depressed against the spring 91 until the lug 92 aligns with the end of plunger 78 in the starting valve device 66 following which said lever will be rocked in a counter-clockwise 30 direction for actuating said plunger into seating engagement with the release valve 77 to close the atmospheric connection to chamber 74 and to then actuate pin 82 to unseat the supply valve 72. Fluid under pressure from the feed valve device 67a present in chamber 71 will then flow past the supply valve 72 to the release valve chamber 74 and thence into passage 106.

Fluid under pressure thus supplied to passage 106 will flow to piston chamber 103 in the vent 40 valve device 67 and there act on piston 101 to move it against spring 104 for unseating the valve 96 against spring 96a. Upon unseating of valve 96 the air compressing chambers 15 in the free piston air compressor 1 and the storage reservoir 18a will be opened to atmosphere through pipe 18 and passage 100 leading to the valve chamber 97 and thence past the open valve 96 to chamber 98a and through the atmospheric passage 99, it being apparent that the air compressing chambers 15 are open to pipe 18 past the discharge valves 17 therefor. The storage reservoir 18a is preferably of relatively small volume, such as 5 cubic feet as will be employed in connection with certain portable air compressing units, so that if partially charged at the time of starting the compressor 1, the dissipation of such fluid by operation of the vent valve device 67 as just described, will not be material. If the reservoir 18a were of greater volume, as might be employed in a stationary air supply system, a check valve (not shown) might be provided between said reservoir and pipe 18 to hold fluid pressure in said reservoir at the time of venting said pipe through the vent valve device 67.

Fluid under pressure supplied to passage 106 by operation of the starting valve device 66 will also flow through choke 140 into chamber 139 and thence through passage 138 into piston chamber 137 of the shuttle valve device 68. The flow capacity of the choke 140 and size of volume 70 139 are so related that sufficient pressure will be obtained in chamber 137 of the shuttle valve device 68 to move piston 135 against spring 136 immediately following opening of vent valve 96 in the vent valve device 67, although the piston 135

may operate in unison with piston 101 under the present condition. The movement of piston 135 against spring 136 will shift the valve 126 out of engagement with seat 121 and into engagement with seat 129 thereby disconnecting pipe 21 and the direct bounce chambers 20 from pipe 128a leading to the direct bounce governor device 130 and opening the former pipe and thereby the direct bounce chambers to the atmospheric passage 132, it now being seen that both the direct bounce chambers 20 and the air compressing chambers 15 in the free piston air compressor 1 are open to atmosphere.

Fluid under pressure supplied by the starting valve device 66 to passage 106 will also flow through pipe 46 to the two positioning cylinder devices 31 and 32 and actuate the pistons 33 and 40 therein to move the respective rods 41 into contact with the ends of the respective racks 22 and 23 and then through said racks actuate the bars 26 and 28 to move the two piston assemblies of the air compressor in a direction away from each other and to the position for starting in which the direct bounce pistons 6 will be disposed in the respective safety spaces 30 in contact with the end walls thereof, it being noted that such movement is unopposed by pressure of fluid in either the air compressing chambers 15 or direct bounce chambers 20 since said chambers are open to atmosphere and vented at this time. As the two power pistons 4 are thus moved apart the power chamber 7 will be first opened to the exhaust port 9 and then to the scavenger port 10 insuring a charge of fresh air in said chamber from the scavenger receiver 13.

As the two piston assemblies are moved from their innermost position to their outermost position for starting, by operation of the positioning cylinder devices 31 and 32 as just described, the movement from the innermost position will withdraw the one rack 22 from contact with plunger 212 in the direct bounce governor device 130 whereupon spring 201 will seat valve 200 to prevent further venting of fluid under pressure from diaphragm chamber 137. The pressure of fluid in chamber 137 will then increase by the supply through choke 169 to substantially the same pressure as provided by the feed valve device 67a in passage 162 and this pressure acting on diaphragm 185 will deflect said diaphragm to close valve 176 and open valve 173. Upon opening of valve 173 fluid under pressure will be vented from piston chamber 170 to passage 175 and thence to chamber 165 and pipe 128a at a rate exceeding the rate of supply to chamber 170 through choke 171 in piston 169, whereupon the higher pressure of fluid in chamber 160 acting on the opposite side of piston 169 will actuate said piston to open the supply valve 163 to permit flow of fluid under pressure from chamber 166 to chamber 165 and pipe 128a. As the pressure of fluid in chamber 165 is thereby increased it will reduce the flow from piston chamber 170 past the open valve 173 and permit the pressure in chamber 170 to increase by flow through the choke 171, until finally the differential in pressures in chambers 170 and 160 at opposite sides of the piston 169 will become reduced to a point where spring 168 will close the supply valve 163. Following closing of the supply valve 163, the pressure in chamber 165 and pipe 128a will equalize through choke 171 in piston 169 and past the open valve 173 with that in the supply passage 162. The valve 173 will remain open at this time under pressure of fluid in chamber 137 acting on diaphragm 185

since chamber 183 at the opposite side of the diaphragm is vented with the direct bounce chamber 20 through the shuttle valve device 68.

With the valve 126 in the shuttle valve device 68 seated on seat 129 the supply valve 163 in the direct bounce governor device will be only momentarily opened for charging the relatively small volume of chamber 165 and pipe 128a under the condition being described. This operation of the direct bounce governor device 130 is not significant at the stage in the starting operation under consideration, but the purpose will be brought out hereinafter.

By the time the direct bounce pistons 6 move into contact with the end wall of safety spaces 30, under action of the positioning cylinder devices 31, 32, the bar 26 connecting the racks 22 will have engaged plunger 78 in the timing valve device 114 and actuated the valves therein to establish communication between pipe 161 supplied with fluid under pressure from the feed valve device 67a and pipe 113 leading to the sequence valve device 69. Fluid under pressure will thus be supplied to pipe 113 from which it will flow through passage 112 in the sequence valve device 69 and past the valve 107 therein which at this time is unseated from seat 111, to pipe 54 leading to the locking devices 47. Pressure of fluid thus obtained in piston chambers 53 of the locking devices will actuate pistons 49 against springs 52 for operating the bell cranks 57 to move the rollers 59 into position for contact with the respective surfaces 61 on the rods 26 and 28 with a force which will hold the two piston assemblies apart upon subsequent release of fluid under pressure from the positioning cylinder devices 31 and 32 and charging of the direct bounce chambers 20 with fluid under pressure.

After the locking devices 47 have been operated to their locking positions, as just described the operator will let go of the lever 86 whereupon spring 91 will return said lever to its normal position in which it is shown in the drawing and in which the lug 92 is disposed above the projecting end of the plunger 78 in the starting valve device 66. In the starting valve device 66 spring 83 will then seat valve 72 to cut off further supply of fluid under pressure to passage 106 while spring 88 will move the plunger 78 out of contact with the release valve 77 for opening said passage to atmosphere.

Upon opening passage 106 to atmosphere fluid under pressure will be released from chamber 37 in the positioning cylinder devices 31 and 32 whereupon the pistons 33, 40 therein will be returned to their normal position, in which they are shown in Fig. 3, by action of springs 36, 44 and 45.

Upon release of fluid under pressure from passage 106 fluid under pressure will be also released from piston chamber 103 in the vent valve device 67 whereupon spring 104 will actuate piston 101 back to its normal position, in which it is shown in the drawing, in order to permit closing of valve 96 by spring 96a. The closing of valve 96 will disconnect from atmosphere the passage 100 and thereby pipe 18, the storage reservoir 18a and air compressing chambers 15.

Immediately following closing of the valve 96 in the vent valve device 67 the pressure of fluid in chamber 137 in the shuttle valve device 68 will become sufficiently reduced through choke 140 and the vented passage 106 to permit spring 136 to return said piston to its upper position in which it is shown in the drawing for unseating

valve 126 from seat 129 and for seating it against seat 131. The seating of valve 126 against seat 131 will close the atmospheric connection to the direct bounce chambers 20 via passage 132 and open said chambers to pipe 128a leading to the direct bounce governor device 130.

Upon operation of the shuttle valve device 68 to disconnect the direct bounce chambers 20 from atmosphere and to connect them to pipe 128a leading to the direct bounce governor device 130, the pressure of fluid in chamber 165, and thereby in piston chamber 170 which at this time is open to chamber 165 past the valve 173, will promptly reduce by flow into the direct bounce chambers 20. Upon this reduction in pressure in chamber 170 the pressure of supply fluid in chamber 160 at the opposite side of piston 169 will actuate said piston to unseat valve 163 against the opposing force of spring 168 whereupon fluid under pressure from passage 162 will flow past said valve to chamber 165 and then into the direct bounce chambers 20 for charging said chambers.

As fluid under pressure is thus supplied to the direct bounce chambers 20 it will flow by leakage past the direct bounce pistons 6 into the safety spaces 30 and act on the ends of said pistons which will move said pistons out of said spaces and bring the ends of the rods 26, 28 into contact with the respective rollers 59 of locking devices 47 which will then temporarily stop further movement of said pistons. As the direct bounce pistons 6 thus move out of the safety spaces 30 the supply valve 72 in the timing valve device 114 will become seated but the release valve 77 will remain seated as the plunger 78 is moved with the respective rack 23 by pressure of fluid in chambers 74 acting on the piston portion 231 of said plunger, whereby the fluid under pressure in the locking devices 47 will be bottled up to maintain said devices effective.

The piston 116 in the sequence valve device 69 is at this time seated by spring 125 against the annular seat rib 123, and the chamber 124 within said seat rib being open to the direct bounce chambers 20 by way of passage 128 and pipe 24, will become charged with fluid at substantially the same time and to substantially the same pressure as effective in the direct bounce chambers. When the pressure of fluid thus obtained in the direct bounce chambers 20 and in chamber 124 of the sequence valve device 69 is thus increased to a chosen degree, such as 425 pounds, such pressure will overcome the opposing force of spring 125 on the piston 116 and start said piston moving away from the seat rib 123. As the piston 116 thus moves out of contact with the seat rib 123 the pressure of fluid effective in chamber 124 within said rib will equalize into chamber 120 encircling said rib thereby subjecting the full area of piston 116 to such pressure which will create a force so exceeding that of spring 125 as to promptly actuate said piston to move valve 107 out of contact with seat 109 and into contact with seat 111. This movement of valve 107 into contact with seat 111 will close communication between the timing valve device 114 and the locking devices 47 while the disengagement of said valve from seat 109 will open pipe 54 from said locking devices to atmosphere through a passage 110, whereby the fluid under pressure present in chambers 53 in the locking devices will be suddenly released. The springs 52 in the locking devices 47 plus the pressure of fluid in the direct bounce chambers 20 acting through the direct bounce pistons 6

on rods 26, 28 will then disengage said locking devices from said rods and permit said pressure of fluid to move the two piston assemblies from their outer positions in the direction of each other.

As the two piston assemblies thus move under pressure of fluid in the direct bounce chambers 20, the plunger 78 of the timing valve device 114 will move with the respective rack 23 until the release valve 77 therein is unseated by engagement with shoulder 84 whereupon the fluid under pressure remaining in the release valve chamber 74 and connected pipe 113 will be vented through said plunger to atmosphere. When the pressure in chamber 74 acting on the portion 231 of the plunger is thus sufficiently reduced the spring 83 will return said plunger to its normal position in which it is shown in the drawing and in which it will not be contacted by the respective rack 23 during subsequent running of the machine. When the release valve 77 is unseated by shoulder 84 as just described the differential in fluid pressures acting thereon will become so reduced as to permit spring 232 to move said valve out of contact with shoulder 84 so that said valve will remain open as the plunger 78 returns to its normal position, as just mentioned.

As the piston assemblies are moved inwardly toward each other under pressure of fluid in the direct bounce chambers 20 as just described the power pistons 4 will close first the scavenger port 10 and then the exhaust port 9, following which the air thus trapped between the two power pistons will be compressed and at the proper time the injector 62 will be operated by the cam 63 to inject fuel into the power chamber 7 through the nozzle 8 to provide compression ignition for developing power to stop inward movement of the piston assemblies and to drive them apart. It will be noted that since the pipe 18 and storage reservoir 18a were vented to atmosphere preliminary to starting, that the fuel control motor 216 will position rack 64 to provide for a maximum supply of fuel by the injector 62 on the initial starting stroke of the piston assemblies.

As the two piston assemblies move inwardly on their initial stroke the air present in the scavenger compressing chambers 11 will be forced past the discharge valves 14 into the scavenger receiver 13, the air compressing chambers 15 will be filled with air by way of the intake valves 16, while the pressure of fluid in the direct bounce chambers 20 will reduce as the volume of said chambers is suddenly increased by the inward movement of the two direct bounce pistons 6. As the piston assemblies then move apart on their initial power stroke by the force created by combustion of fuel in the power chamber 7, the scavenger pressure chambers 11 will be refilled with air past the intake valves 12 while the air present in the air compressing chambers 15 will be discharged past the discharge valves 17 into the pipe 18 and thence to the storage reservoir 18a. Also on this initial outward stroke of the piston assemblies air present in the direct bounce chambers 20 will be compressed to a degree which, co-acting with the pressure created in the air compressing chambers 15, will stop said piston assemblies short of entering the safety spaces 30 and provide energy for returning said pistons on the following inward stroke.

The direct bounce governor device 130 is automatically operative during running of the ma-

chine to so regulate the amount of air in the direct bounce chambers 20, with respect to the amount of fuel supplied to power chamber 7 for driving the pistons apart, and also with respect to the energy of the air remaining in the air compressing chambers 15 at the end of the outward stroke of the piston assemblies, as to stop the piston assemblies at the proper position on their outward stroke, and to provide the energy required for returning said assemblies to a chosen inner position.

When the direct bounce chambers 20 are initially charged with fluid under pressure by the direct bounce governor device 130 preparatory to starting the compressor, the pressure of such fluid may, as above mentioned, be for instance 425 pounds at the time the sequence valve device 69 operates to effect release of the locking devices 47 to permit the initial inward stroke of the piston assemblies. At this time the pressure of fluid in diaphragm chamber 187 of the direct bounce governor device will be of substantially the same value as that supplied by feed valve device 67a, while in chamber 183, which is connected to the direct bounce chambers 20 through the small flow capacity pipe 188, the pressure of fluid at the time the sequence valve device 69 operates, may be somewhat less than in the direct bounce chambers 20, so that the diaphragm 185 will still hold the valve 173 open for venting piston chamber 170 to the direct bounce chambers 20 to permit the supply pressure in chamber 160 to hold said piston in the position in which the valve 163 is still open for supplying fluid under pressure to the direct bounce chambers 20.

On the initial inward stroke of the piston assemblies, however, the pressure of fluid in diaphragm chamber 183 will start gradually reducing through pipe 188 due to the sudden reduction in pressure in the connected direct bounce chambers 20 but this reduction in pressure in chamber 183 in itself will be of no immediate consequence since it is effective merely to permit diaphragm 185 to hold the valve 173 open for continuing the supply of fluid under pressure to the direct bounce chambers by way of the open supply valve 163.

The energy of the air in the direct bounce chambers 20 will be greater on the initial few inward strokes of the piston assemblies than required during subsequent running, and as a result these inward strokes of said assemblies will be longer than desired for running. Due to this, on each inward stroke of the piston assemblies the respective rack 22 will operate plunger 212 in the direct bounce governor device to unseat the valve 200 a distance equal substantially to the overstroke of said piston assemblies. This unseating of valve 200 will release fluid under pressure from chamber 187 to the direct bounce chambers 20 at a rate exceeding the supply through choke 189 to permit a reduction in pressure of fluid in said chamber governed by the length of time which the valve 200 is unseated or the distance which it is unseated by the plunger 212. After one or more inward strokes of the piston assemblies the pressure of fluid in diaphragm chamber 187 will be thus so reduced with respect to the opposing pressure of fluid in chamber 183 as to permit the deflection of diaphragm 185 by said opposing pressure to permit closing of the supply valve 173, whereupon the pressure of fluid in piston chamber 170 will become equalized through choke 174 and passage 172 with that

in the supply passage 162 to permit closing of the valve 163 by spring 168. After one or more further overstrokes of the piston assemblies in the inward direction the intermittent opening of valve 200 will effect sufficient further reduction in pressure of fluid in diaphragm chamber 187 to permit the pressure of fluid in chamber 183 to deflect diaphragm 185 further in the direction of the left hand to permit opening of the release valve 176 for thereby releasing fluid under pressure from the direct bounce chambers 20. As the amount of fluid in the direct bounce chambers 20 is thus reduced the length of the inward, overstroke of the piston assemblies will be correspondingly decreased, until eventually, the intermittent but reduced opening of valve 200 with respect to the flow capacity of choke 189 for supplying fluid under pressure to chamber 187 will provide a pressure in chamber 187 so related to the mean direct bounce chamber pressure effective in chamber 183 at the opposite side of diaphragm 185 that said diaphragm may remain in a position in which the valve 176 is closed as well as the valve 173. In case of leakage of fluid under pressure from the direct bounce chambers 20 to, for instance, the air compressing chamber 15, which would tend to reduce the inward stroke of the piston assemblies, the valve 200 will be unseated on the inward stroke to a corresponding less extent or for a less period of time so that the pressure of fluid in diaphragm chamber 187 will be reduced only to a degree sufficiently in excess of that in chamber 183 to maintain the valve 173 unseated to a degree just sufficient to offset such leakage.

It will thus be seen that during the first few strokes of the free piston air compressor, the direct bounce governor device 130, as controlled by the overstroke of the piston assemblies in the inward direction will automatically reduce the amount of air in the direct bounce chambers 20 to the degree required to cause movement of the piston assemblies only to the chosen inner position. The adjusting screw 207 in the direct bounce governor device is provided for adjusting the seat for valve 200 for in cooperation with said valve determining the end of the inward stroke of the piston assemblies during running of the machine.

The energy of the air in the clearance space in the air compressing chambers 15 at the end of the outward air compressing stroke of the piston assemblies acts in conjunction with the energy of the air in the direct bounce chambers 20 for moving the piston assemblies inwardly, and the former energy varies in accordance with the pressure of air in pipe 18 and storage reservoir 18a, but the direct bounce governor device 130 will automatically vary the amount of air in the direct bounce chambers 20 inversely in proportion to the energy of the air in the air compressing chambers 15 at the end of the air compressing stroke so that the combined energies will always be such as to maintain the desired inner dead center point of the power pistons as will be apparent from the above description.

The pressure of spring 229 in the fuel control motor 218 is such as to maintain the diaphragm 219 and thereby the lever 222 and fuel control rack 64 in the position in which they are shown in the drawing, providing for a maximum supply of fuel to the power chamber 7, until the pressure of fluid in the storage reservoir 18a and pipe 18 effective in diaphragm chamber 220 is increased to a chosen degree, such for example

as 90 pounds. As this pressure in diaphragm chamber 220 is further increased the diaphragm 219 is adapted to move against the spring 229 for operating the rack 64 to reduce the supply of fuel to the power chamber 7 correspondingly. As the supply of fuel to the power chamber 7 is thus reduced the force developed on the power pistons 4 by the combustion of such fuel and thereby the outward stroke of the piston assemblies will be correspondingly reduced, until at the time a chosen maximum pressure (100 pounds) is obtained in the storage reservoir 18a and diaphragm chamber 220, the lever 224 and rack 64 will obtain an idle position to provide a minimum supply of fuel to the power chamber 7. When the supply of fuel to the power chamber 7 is thus reduced to a minimum the explosive force thereof on the power piston assemblies will be insufficient to increase the pressure of air in the air compressing chambers 15 to a degree exceeding that already present in the storage reservoir 18a under which condition the piston assemblies will merely idle under the reduced explosive force in chamber 7, and against the direct bounce pressure in the direct bounce chambers 20 without compressing air into the storage reservoir 18a, the direct bounce governor device 130 operating at all times to maintain a sufficient quantity of air in the direct bounce chambers 20 for moving the piston assemblies to their inner chosen position.

As before described, pipe 18 is connected through the unloading valve device 70 to pipe 146 leading to the auxiliary high pressure compressor 147. The high pressure compressor 147 is operated by the pinion gear operated shaft 25 at all times the free piston compressor 1 is in operation and takes air from pipe 146, at the pressure present in the storage reservoir 18a, and compresses it into pipe 148 and thence through passage 158 and past the check valve 156 in the unloading device 70 to passage 155 and through pipe 95 to the high pressure reservoir 94. The pressure of fluid thus obtained in the high pressure reservoir 94 is effective in chamber 154a on piston 151 of the unloading valve device 70 and when such pressure is increased to the chosen degree, for instance 650 pounds, such pressure will overcome the opposing force of spring 154 on said piston and actuate said piston to unseat the check valve 141. With the check valve 141 unseated the discharge pipe 148 from the high pressure compressor 147 will be opened to the intake pipe 146 for said compressor and to pipe 18 connected to the storage reservoir 18a, whereby the high pressure compressor 147 will be unloaded and further supply of fluid under pressure to the high pressure reservoir 94 will be terminated.

The high pressure reservoir 94 constitutes the source of supply of fluid under pressure by way of feed valve device 67a to the direct bounce governor device 130 for supply to the direct bounce chambers 20 during operation of the compressor 1, so that as fluid under pressure is used from said reservoir during such operation the unloading device 70 will automatically operate to render the high pressure compressor 147 either effective or ineffective to supply fluid under pressure to said reservoir in order to maintain the pressure in said reservoir within limits determined by the pressure of spring 154 acting on the unloading piston 151.

In starting the free piston compressor the choke 140 and valve 139 restrict release of fluid

under pressure from chamber 137 in the shuttle valve device 68 with respect to the release of fluid under pressure from the positioning cylinder devices 31, 32, as above described, whereby, upon release of the operator's handle 86 a slight delay (perhaps one second) in operation of the shuttle valve device 68 to connect the direct bounce chambers 20 to the direct bounce governor device 130 results. When the direct bounce chambers 20 are thus connected to the direct bounce governor device said chambers will charge with fluid under pressure at a very fast rate, and immediately following, the sequence valve device 69 will operate to effect release of the locking devices 47. The purpose of the delay above mentioned is to ensure that the piston rods 41 of the positioning cylinder devices 31, 32 will be returned to their normal position, in which they are shown in the drawing, before the locking devices 47 release the piston assemblies for movement on their initial inward stroke, so as to prevent the rods 26, 28 striking the ends of said piston rods on said stroke.

Further in connection with starting the compressor 1, piston 116 in the sequence valve device 69 actuates valve 107 to open pipe 54 from the locking devices 47 to atmosphere when the pressure of fluid in the direct bounce chambers 20 is increased to a certain high pressure, such as 425 pounds, as above described. On the initial inward stroke of the piston assemblies of the compressor 1 the pressure in chambers 124, 120 of the sequence valve device may reduce by flow back to the direct bounce chambers 20 to a sufficiently low degree to permit spring 125 to return the parts of said device to the position in which they are shown in the drawing and in which pipe 54 from the locking devices 47 is open to pipe 113 from the timing valve device 114. This has no effect upon operation of the locking devices 47 however, since the supply of fluid under pressure to pipe 113 by way of the timing valve device 114 is terminated upon the initial inward stroke of the piston assemblies. However, on the initial power stroke of the power pistons 4 the pressure of fluid in the direct bounce chambers 20 and thereby in chamber 124 of the sequence valve device 69 may be increased to a sufficient degree to effect movement of the piston 116 out of engagement with the seat 123, but without any effect upon operation of the compressor. The piston 116 in the sequence valve device 69 may thus be alternately unseated and reseated during the first few power and return strokes of the power pistons 4, but when the amount of fluid under pressure in the direct bounce chambers 20 becomes reduced, as previously described, to that degree which will not cause overstroking of the power pistons 4 in the inward direction, the maximum pressure of fluid that will then be obtained in the direct bounce chambers 20, for instance 225 pounds, will be insufficient to move the piston 116 out of contact with seat rib 123 following which, that is, during subsequent running of the compressor 1, the piston 116 will remain in contact with said seat rib.

In order to stop operation of the compressor 1 the supply of fuel to the power chamber 7 need only be cut off by any suitable means (not shown), whereupon the piston assemblies will move to their normal inner position upon the initial inward stroke following the cutting-off of fuel. The pressure of compressed air, but less combustion of fuel, in power chamber 7 will then move the piston assemblies apart, but on a shortened outward stroke, following which they

will move inward on a shortened stroke. Such oscillation of the piston assemblies may continue for a few, but ever decreasing length of strokes until eventually said pistons come to rest in some intermediate position in which the valve 200 in the direct bounce governor device 130 will be seated. With the valve 200 seated, the pressure in diaphragm chamber 187 will increase to a degree sufficiently exceeding that in chamber 183 to actuate said diaphragm to open the supply valve 173 whereupon fluid will be supplied to the direct bounce chambers 20 and create a force on the direct bounce pistons 6 exceeding the force created by pressure in the power chamber 7 on the power pistons 4. As the fluid under pressure in the power chamber 7 is then dissipated by leakage, pressure in the direct bounce chambers 20 will move the piston assemblies toward each other until the valve 200 in the direct bounce governor device is opened to a degree to provide for venting of fluid under pressure from diaphragm chamber 187 at a rate exceeding the rate of supply through choke 189. When this condition is obtained, the pressure in diaphragm chamber 187 will equalize into the direct bounce chambers 20 and diaphragm chamber 183. The diaphragm 185, having a greater area exposed to pressure in chamber 183 than in chamber 181, will then deflect in the direction to open the release valve 176. The fluid under pressure in the direct bounce chambers 20 and diaphragm chambers 183 and 187 will then be dissipated to atmosphere without any change occurring in position of the parts of the piston assemblies or the direct bounce governor device 130.

After the compressor 1 is stopped it will be noted that the open valve 176 will permit a continuous flow of fluid under pressure from the high pressure reservoir 94 to atmosphere by way of the feed valve device 67a and the open valve 200. This loss is relatively slight, but if the compressor is to remain stopped for any length of time the cut-off valve 230 will be closed to conserve the air in the high pressure reservoir 94 for subsequent starting of the machine.

Summary

From the above description it will now be seen that I have provided a relatively simple control apparatus for a free piston machine whereby the machine will start automatically in response to manual operation of a starting device and will automatically operate after starting to maintain a supply of compressed air for external use.

Having now described the invention, what I claim as new and desire to secure by Letters Patent, is:

1. Apparatus for controlling starting of a free piston machine of the type having direct bounce and air compressing chambers in which energy of compressed air is adapted to move said piston from an outer position to an inner position to provide compression ignition, said apparatus comprising valve means for venting both of said chambers, means for effecting movement of said piston to said outer position, an operator's control device for effecting operation of both of said means substantially in unison, and means operable in said outer position for supplying fluid under pressure to said direct bounce chamber.

2. Apparatus for controlling starting of a free piston machine of the type having direct bounce and air compressing chambers in which energy of compressed air is adapted to move said piston from an outer position to an inner position to

provide compression ignition, said apparatus comprising valve means operable by fluid under pressure to establish a vent from said chambers and upon release of fluid under pressure to close said vent, means operable by fluid under pressure to move said piston to said outer position and rendered ineffective upon release of fluid under pressure, an operator's control device for substantially simultaneously either supplying fluid under pressure to actuate both of said means or for releasing fluid under pressure therefrom, and means operable in said outer position for supplying fluid under pressure to said direct bounce chamber.

3. Apparatus for controlling starting of a free piston machine of the type having direct bounce and air compressing chambers in which energy of compressed air is adapted to move said piston from an outer position to an inner position to provide compression ignition, said apparatus comprising automatic means for regulating pressure of fluid in said direct bounce chamber, valve means operable by fluid under pressure to close communication between said automatic means and direct bounce chamber and to open a vent to said direct bounce chamber, other valve means operable by fluid under pressure for opening a vent to said air compressing chamber, an operator's control device for supplying fluid under pressure to actuate both of said valve means substantially simultaneously and for releasing fluid under pressure from both of said valve means simultaneously, and means operable by fluid under pressure supplied by said operator's control device to move said piston to said outer position and rendered ineffective upon release of such fluid under pressure.

4. Apparatus for controlling starting of a free piston machine of the type having a bounce chamber in which energy of compressed air is adapted to move said piston from an outer position to an inner position to provide compression ignition for starting the machine, comprising an operator's control element, means operable in response to operation of said element by the operator to open a vent from said chamber and to effect movement of said piston to said outer position and operable in response to release of said lever by the operator to close said vent and to effect a supply of fluid under pressure to said chamber, locking means operable automatically in said outer position to lock said piston against movement, and means operable in response to a chosen increase in pressure in said chamber to release said locking means.

5. Apparatus for controlling starting of a free piston machine of the type having a bounce chamber in which energy of compressed air is adapted to move said piston from an outer position to an inner position to provide compression ignition for starting the machine, comprising an operator's control element, vent means for opening a vent from said chamber, positioning means for moving said piston to said outer position, means operable in response to manual operation of said element to effect operation of said vent means and positioning means and in response to release of said element by the operator to render said vent means and positioning means ineffective and to also supply fluid under pressure to said chamber, locking means rendered effective in said outer position to hold said piston against movement, and means automatically operative upon a chosen increase in pressure in said chamber to render said locking means ineffective.

6. Apparatus for controlling operation of a free piston machine having a direct bounce chamber in which energy of compressed air is adapted to move said piston from an outer position to an inner position to provide compression ignition, said apparatus comprising automatic means for supplying fluid under pressure to said direct bounce chamber and comprising means cooperative with said piston at said inner position to release fluid under pressure from said direct bounce chamber for regulating the pressure in said bounce chamber, shuttle valve means operable by fluid under pressure to disconnect said direct bounce chamber from said automatic means and to open it to a vent and operable from release of fluid under pressure to disconnect said direct bounce chamber from said vent and open it to said automatic means, positioning means operable by fluid under pressure to move said piston to said outer position and rendered ineffective upon release of fluid under pressure, operator's control means selectively operable to either supply fluid under pressure simultaneously to both said shuttle valve means and positioning means or to release fluid under pressure simultaneously therefrom, locking means operable by fluid under pressure to hold said piston in said outer position and rendered ineffective upon release of fluid under pressure, valve means operable in said outer position of said piston to supply fluid under pressure to said locking means, and means operable upon a chosen increase in pressure in said direct bounce chamber to cut off the supply of fluid under pressure to said locking means and to release the fluid pressure therefrom.

7. Apparatus for controlling starting of a free piston machine of the type having a bounce chamber in which energy of compressed air is adapted to move said piston from an outer position to an inner position to provide compression ignition, comprising supply means for supplying fluid under pressure to said chamber, positioning means for moving said piston to said outer position, control means operable to open said chamber to either said supply means or to a vent, locking means for holding said piston in said outer position against movement by pressure of fluid in said chamber, means adapted for operation upon a chosen increase in pressure in said chamber to render said locking means ineffective, and control means for effecting operation of said positioning means and of the first named control means to open said chamber to said vent substantially in unison and for also rendering said positioning means ineffective and for effecting operation of said first named control means to open said chamber to said supply means, and means for delaying operation of said first named control means to open said chamber to said supply means with respect to rendering said positioning means ineffective.

8. Apparatus for controlling starting of a free piston machine of the type having a bounce chamber in which energy of compressed air is adapted to move said piston from an outer position to an inner position to provide compression ignition, comprising supply means for supplying fluid under pressure to said chamber, positioning

means operable by fluid under pressure to move said piston to said outer position, shuttle valve means operable by fluid under pressure to open said chamber to a vent and upon release of fluid under pressure to open said chamber to said supply means, locking means for holding said piston in said outer position against movement by pressure of fluid in said chamber, means responsive to a chosen increase in pressure in said chamber to render said locking means ineffective, control means for at one time simultaneously supplying fluid under pressure to said positioning means and shuttle means, and for at another time simultaneously releasing fluid under pressure from said positioning means and shuttle means, and means for delaying release of fluid under pressure from said shuttle means with respect to release of fluid under pressure from said positioning means.

9. Apparatus for controlling starting of a free piston machine of the type having a bounce chamber in which energy of compressed air is adapted to move said piston from an outer position to an inner position to provide compression ignition and said piston being movable past said outer position, comprising positioning means for moving said piston past said outer position, locking means operable by fluid under pressure for holding said piston for movement from said outer position to said inner position and rendered ineffective upon release of fluid under pressure, valve means operable by said piston beyond said outer position to supply fluid under pressure to said locking means, and to hold such fluid under pressure in said locking means in said outer position, supply means for supplying fluid under pressure to said chamber, shuttle means for selectively connecting said chamber either to said supply means or a vent, operator's control means for substantially simultaneously, at one time effecting operation of said positioning means and of said shuttle means to connect said chamber to said vent and for at another time rendering said positioning means ineffective and effecting operation of said shuttle means to connect said chamber to said supply means, and means operable upon a chosen increase in pressure of fluid supplied to said chamber by said supply means to release fluid under pressure from said locking means.
